Primary Examiner — Ricky Pham(57) **CLAIM**We claim the ornamental design for a multicooker, as shown
and described.**DESCRIPTION**FIG. 1 is a front perspective view of the multicooker of the
present invention;FIG. 2 is a rear perspective view of the multicooker of the
present invention;FIG. 3 is a front elevation view of the multicooker of the
present invention;FIG. 4 is a rear elevation view of the multicooker of the
present invention;FIG. 5 is a left-side elevation view of the multicooker of the
present invention;FIG. 6 is a right-side elevation view of the multicooker of the
present invention;FIG. 7 is a top plan view of the multicooker of the present
invention; and,FIG. 8 is a bottom plan view of the multicooker of the
present invention.The broken lines in the figures are for contextual purposes
or show the environment and form no part of the claimed
design.**1 Claim, 8 Drawing Sheets**(56)
